UNITED STATES PATENT OFFICE.

LOUIS A. WEBER AND JACOB ALLAN WEBER, OF CLEVELAND, OHIO.

FOLDING BIER AND TRUCK.

Application filed February 10, 1925. Serial No. 8,170.

To all whom it may concern:

Be it known that we, LOUIS A. WEBER and JACOB ALLAN WEBER, citizens of the United States, residing at Cleveland, in the county of Cuyahoga and State of Ohio, have invented certain new and useful Improvements in Folding Biers and Trucks, of which the following is a specification.

This invention relates to improvements in combined folding biers, or coffin supports, and trucks.

Among the objects of the invention is to provide a support structure on which a coffin can be readily placed and removed, and which, when a coffin is mounted thereon, can be moved about without apparent effort, and that is capable, when not in service, of being folded into a compact form to be easily carried by one person.

Another object is to provide a bier that may be upholstered, or appropriately decorated, so as to give a sightly and pleasing appearance when in use as a bier.

A further object is to provide a structure of this character that is light and simple, ornamental, not liable to be broken or get out of repair, which is durable, and easy to manipulate.

Other objects will appear from the detailed description to follow, and the invention will be clearly defined and pointed out in the claims.

A structure embodying the features of our invention is illustrated in the accompanying drawing, forming a part of this specification, in which—

Fig. 1 is a top plan view of the improved structure in extended condition. Fig. 2 is a side elevation, and Fig. 3 is a top plan of the structure when folded for transportation.

In the drawing and throughout the description similar reference characters are employed to designate corresponding parts.

Referring to the drawing, 1 represents a thin rectangular body member, vertically disposed, with the longer edges 1^a and 1^b as top and bottom respectively. The ends of the body member 1 are double beveled, or of angular formation, as shown at 1^c, and wings 2 are attached vertically to the beveled edges by hinges 3. The wings 2 and the body 1 are of the same vertical dimension and are so hinged that their top, and bottom edges, are in the same horizontal planes, respectively.

The body 1 and the wings 2 may be panelled and upholstered, as shown, or they may be made otherwise more or less ornamental or decorative.

Casters 4 are attached to the bottom of the structure, the body 1 being preferably provided with two, while each of the wings carries one of said casters.

This novel construction allows the wings 2 to be folded back against the body 1 in compact form, as shown in Fig. 3, and to be extended, or spread out in V-form, as shown in Figs. 1 and 2, thereby forming a staunch support for a casket, and a bier that has an attractive appearance. The casters make the structure portable when in service loaded, or when in a folded condition out of service. The beveled edge faces 1^c provide stops which position the wings 2 in their extended arrangement.

It is obvious that such changes in the form, proportion, and minor details of construction of the parts as fairly fall within the scope of our invention may be made without departing from the spirit or sacrificing any of the advantages thereof.

Having fully described our invention, what we claim and desire to secure by Letters Patent is:

1. A bier comprising a body panel vertically disposed and having oppositely beveled edges at each end, wing panels hinged to said edges and adapted to be arranged in V-form at the ends of the body panel and to be folded against opposite sides of the body panel with the free ends of the wings on each side of the body panel adjacent to each other, casters on the lower edges of said body panel and wing panels, and said beveled edges serving as stops to co-operate with said wing panels to position the latter in their extended arrangement.

2. A bier comprising a body panel vertically disposed, a pair of wing panels hinged to each end of said body panel and adapted to extend therefrom in V-form, and the wing panels of each pair being adapted to be folded against opposite sides of the body panel with the wing panels on each side of the body panel in end-to-end arrangement in the same plane.

In testimony whereof we affix our signatures.

LOUIS A. WEBER.
J. ALLAN WEBER.
